UNITED STATES PATENT OFFICE.

RALPH E. HEISEL, OF CHILlicothe, OHIO, ASSIGNOR TO THE MEAD PULP & PAPER COMPANY, OF DAYTON, OHIO, A CORPORATION OF OHIO.

PAPER MACHINERY.

Application filed March 7, 1927. Serial No. 173,409.

This invention relates generally to paper-making apparatus, and in particular to apparatus for cleaning and scraping the surface of a revolving roll, cylinder, or the like; and more particularly to apparatus of the character commonly termed a "doctor".

One of the principal objects of this invention is to provide apparatus of this character which is of simple construction, more effective in operation, and in which the parts subject to wear may be easily and quickly replaced.

Other objects and advantages of this invention will be apparent from the following description when taken in connection with the accompanying drawing.

In the drawing in which like characters of reference designate like parts throughout the several views thereof;

20 Fig. 1 is an end elevation of apparatus constructed in accordance with this invention; and

Fig. 2 is a plan view of the apparatus of Fig. 1.

25 As illustrating a preferred embodiment of the invention, there is disclosed in the drawing a doctor comprising, generally a body portion 10 and a removable blade portion 11. The blade 11 cooperates with the surface of a rotatable roll 12, which may be a drying cylinder, press roll, or other roll. The doctor is mounted upon suitable supporting frame-work indicated at 14, which frame-work may also support the roll 12, the construction of the bearing supports of this roll and the supporting frame-work being of conventional character and not illustrated in detail. The doctor is shown as pivotally mounted upon the supporting frame-work, suitable bearing brackets 15 bolted to the frame-work 14 serving to receive the journals 16 of the doctor. The doctor is free to swing about its pivotal mounting, and as shown the blade portion 11 is held against the surface of the roll 12 by the weight of the parts. It is obvious that other types of mounting for the doctor can be employed in accordance with this invention, and that set-screws or other means can be provided in association with the supporting frame-work to maintain the blade of the doctor against the roll with a positive force other than that of its own weight, as is well known.

In use the body portion 10 is mounted upon the supporting frame-work, and the blade

portion is made relatively light and is detachably connected to the main body portion. The body portion comprises a cylindrical tube 23 carrying the journals 16, which tube is fastened to the flat or plate member 24 of the body portion by a plurality of screws or other fastening means 25. Extending transversely across the forward or lower side of the plate member is a block 28 securely fastened in place by a plurality of screws, 65 rivets, or other attaching means 29.

In order to provide for the ready connection of the blade portion 11 to the body portion 10 and to facilitate disassembly or assembly, the blade and body portions are provided with cooperating interfitting surfaces. As shown the block 28 is cut away to provide a groove adjacent the plate member as indicated at 30, one face of the groove being provided with a U-shaped channel 31. The blade portion 11 is adapted for detachable positioning within the groove 30 and is provided with a transversely extending reinforcing strip 33 rigidly fastened to the blade portion by a number of screws or bolts indicated at 34 having projecting heads 35 adapted to loosely fit within this groove. As shown the channel 31 is in the block 28 and the construction is such that the reinforcing strip provides a lower flat surface which is adapted to cooperate with the upper surface of the plate member 24, while the projections or heads 35 extend within the channel 31. The channel thus forms a forwardly and downwardly projecting lip portion indicated at 32 in the block 28, which lip portion cooperates with the projections 35 to prevent the blade portion from sliding forwardly out of engagement with the body portion.

The blade portion 11 may be of any suitable construction as long as sufficient flexibility for desired operation is obtained. As shown the blade portion comprises a flexible metal member 40 which is fastened at one edge to the body portion 10 and at its other edge is riveted to the blade portion proper or scraper 41 which actually contacts during operation with the roll. The scraper 41 is preferably clamped between blocks 42, and the scraper and blocks are rigidly connected to the member 40 by means of rivets or the like 43. The flexible metal member 40 is preferably constructed in the form of a spring blade but may be a plurality of steel strips or springs.

For detachably connecting the blade por-

tion in operative position, set-screws 45, shown to be two in number, are provided. The set-screws pass loosely through suitable openings indicated at 47 in the block 28, and 5 are screw-threaded into suitably located and threaded passages 48 formed through the reinforcing strip 33, the points of the screws being faced against the flat plate member 24. This construction serves to prevent the blade 10 portion from sliding endwise out of operative position. In actual practice, a clearance is provided between the heads 35 of the attaching means 34 to permit the ready insertion of the blade portion, and the desired rigidity of 15 the parts in operative position is obtained by the weight of the body portion pressing down upon the inserted blade portion.

When it is desired to replace the blade of the doctor, it is only necessary to unscrew and 20 remove the set-screws 45 and to withdraw the blade portion 11 endwise from its interfitting engagement with the body portion 10. A single operator can conveniently and easily do this by removing the set-screws 45, and 25 then withdrawing the blade portion. With this construction, the heavy portion of the doctor is permanently secured to its mounting and the replacement of the blade can be effected without disturbing this mounting. 30 The removable portion of the doctor is relatively light and can be conveniently handled by a single operator. During endwise removal of the blade portion, the end opposite that which is being carried by the operator is 35 supported and guided by its interfitting engagement with the body portion.

Upon replacement of the blade portion of the doctor, the operation is merely the opposite of that described for removal. The blade 40 portion is supported so that its cooperating interfitting surface or projection may be inserted endwise within the cooperating groove within the body portion, the blade portion is then moved endwise into operative position, 45 and the set-screws inserted in place.

Preferably the blade portion is constructed in replaceable units, so that an additional or auxiliary blade portion may be readily kept on hand for replacement purposes. Thus 50 when an old blade portion is removed, a new blade portion can be immediately inserted in position, the entire operation requiring only a few minutes, whereby the necessity of a long shut-down of the machine is avoided.

55 The present construction of doctor operates more effectively in actual use in that the tendency of the doctor to vibrate excessively or "chatter" during operation is effectively overcome.

60 While the form of apparatus herein described constitutes a preferred embodiment of the invention, it is to be understood that the invention is not limited to this precise form of apparatus, and that changes may be made 65 therein without departing from the scope of

the invention which is defined in the appended claims.

What is claimed is:

1. A doctor of the character described comprising a body portion, and a separate blade 70 portion having interlocking engagement with and detachably connected to said body portion.

2. A doctor of the character described comprising a metal plate body portion, and a 75 separate relatively light flexible blade portion having interlocking engagement with said body portion to prevent frontwise disengagement, said blade portion being detachably connected to said body portion. 80

3. A doctor of the character described comprising a body portion, a blade portion, said body and blade portions having cooperating interfitting and interlocking surfaces whereby said portions may be assembled in operative position, and means for detachably connecting said portions in said operative position. 85

4. A doctor of the character described comprising a body portion, a blade portion, one 90 of said portions having a transversely extending groove therein, a cooperating projection formed on said other portion, whereby said portions may be moved relatively to each other endwise into interfitting engagement, and means for detachably connecting said portions together in said interfitting engagement. 95

5. A doctor of the character described comprising a metal plate member, a reinforcing block extending transversely of said plate member and attached thereto, said block having a transversely extending groove formed along the length thereof; a separate blade portion, a projection on said blade portion adapted to be received within said groove to prevent the blade portion from sliding forwardly out of said groove but permitting said blade portion to be moved endwise into operative position within said groove, and 100 means for detachably connecting the blade portion to the body portion in said operative position. 110

6. A doctor of the character described comprising a metal plate member, a reinforcing block extending transversely of said plate member and attached thereto, said block having a transversely extending groove formed along the length thereof with a U-shaped channel in one face thereof; a separate blade 115 portion, a transversely extending reinforcing strip, and projecting attaching means connecting said reinforcing strip to said blade portion, said blade portion being adapted to be moved endwise into operative 120 position within said groove with said reinforcing strip adjacent the said plate member, and said projecting attaching means extending within said U-shaped channel to prevent the blade portion from sliding forward- 125 130

ly out of said groove, and means for detachably connecting the blade portion in said operative position.

7. A doctor of the character described comprising a metal plate body portion, a flexible blade portion connected to said body portion adjacent the front end of said body portion, and a rigid transversely extending reinforcing bar substantially thicker than said metal plate portion attached to said metal plate portion adjacent the point of connection of said blade portion.

8. A doctor of the character described comprising a body portion, a separate blade portion adapted to be moved into or out of operative position relative to said body portion, said parts having cooperating guiding surfaces adapted to direct said blade por-

tion into proper operative position relative to said body portion, and means for detachably connecting said portions in said operative position.

9. A doctor of the character described comprising a body portion, a separate blade portion adapted to be moved endwise into or out of operative position relative to said body portion, said parts having cooperating interfitting surfaces for guiding and supporting said blade portion for movement endwise into or out of said operative position, and means for detachably connecting said portions in operative position.

In testimony whereof I hereto affix my signature.

RALPH E. HEISEL.
